United States Patent Office

Des. 195,248
Patented May 21, 1963

195,248

VACUUM CLEANER

Edwin F. Oblinger, Springfield, Ohio, assignor to Parker
Sweeper Company, Springfield, Ohio, a corporation of
Ohio

Filed May 8, 1961, Ser. No. 65,050

Term of patent 14 years

(Cl. D9—2)

FIG. 2

FIG. 1 is a perspective view of a vacuum cleaner, showing my new design;

FIG. 2 is a front elevational view thereof.

The opposite side of the cleaner which is not shown has substantially the same appearance as the side depicted in the drawings, with the exception of the blower as indicated in FIGURE 2.

The dominant features of my design reside in the portions shown in full lines.

I claim:

The ornamental design for vacuum cleaner, as shown and described.
